UNITED STATES PATENT OFFICE.

JAMES CHAPMAN, OF FORFAR, SCOTLAND.

MAKING OF ROADWAYS.

1,277,380.

Specification of Letters Patent. Patented Sept. 3, 1918.

Application filed April 24, 1917. Serial No. 164,087.

To all whom it may concern:

Be it known that I, JAMES CHAPMAN, citizen of Great Britain, and resident of St. Anne's St. James's Road, Forfar, in the 5 county of Forfar, Scotland, have invented certain new and useful Improvements in or Relating to the Making of Roadways, of which the following is a specification.

This invention relates to the making of 10 roadways for vehicular traffic and has for its object to provide a roadway which will minimize the wear and tear of the roads and vehicles using same, prevent dust and also reduce the amount of power required 15 for drawing or driving vehicles.

According to this invention I insert in 20 the road two or more parallel strips of concrete, asphalt, artificial stone or similar material laid in sections previously formed, or molded *in situ* and which may be used alone or which may have metal reinforcement embedded in it, the parallel strips being of such width as to accommodate 25 wheels of varying distances apart.

25 The following description and accompanying drawings show manners of carrying out the invention.

Referring to the drawings:—

Figure I is a transverse section of a roadway 30 in which one pair of surfaces has been laid.

Fig. II is a plan of Fig. I.

Fig. III is a transverse section of a roadway 35 in which three surfaces have been laid for broad and narrow gage traffic.

Fig. IV is a plan of Fig. III.

Fig. V is a transverse section of a roadway 40 in which two pairs of surfaces have been laid.

Fig. VI is a plan of Fig. V.

Figs. VII, VIII, IX and X are sectional views showing modified forms of surfaces 45 embodying my invention.

Fig. XI is a sectional view showing further modified form of surfaces and means for connecting the surfaces.

In the arrangement of Figs. I and II 50 two trenches are prepared in the road *a* of suitable depth, according to the nature of the soil and traffic requirements, and in these trenches are formed continuous lines of reinforced concrete *b* and *c*, parallel with the direction of the road. The reinforced strips or surfaces *b* and *c* are laid in pairs 55 so as to form bearing strips for the wheels of vehicles using the road. In Figs. I and

II a single pair of bearing strips is shown, for use of traffic in either direction if the traffic on the road is not very great.

In the modification shown in Figs. III 60 and IV three surfaces *d*, *e* and *f* are employed to accommodate broad or narrow gaged traffic, the surfaces *d* and *e* being adapted to accommodate the broad or ordinary traffic, and the surfaces *e* and *f* the 65 narrow gage traffic. The surface *e* being common to both broad and narrow gage traffic.

Figs. V and VI show two pairs of surfaces, *g*, *h*, *i*, *j*, one pair being for use of 70 traffic in one direction and one pair for traffic in the other direction. Such an arrangement would probably be found suitable for main high roads where the traffic is considerable and travels quickly. 75

As shown in Fig. VII, the upper surface of the strip is curved in the form of an arc so that the upper edges of the strip are disposed below the surface of the roadway thereby protecting the edges of the 80 strip from the action of vehicle wheels when they are passing onto and off of the strip.

In Fig. VIII, the edges of the strip are also disposed below the surface of the roadway. However in this embodiment the edges 85 are rounded as shown. In Fig. IX, the upper edges of the strip are beveled, this construction also preventing vehicle wheels moving transversely of the strip, from damaging the edges of the strip. 90

Referring now to Fig. X, I have here shown a strip of rectangular formation in cross section which is provided with a metal bar *m*. The upper edge of the bar *m* terminates flush with the upper surface of the strip, so that it forms one edge of the strip and thus prevents wear and damage to the strip by the wheels of the vehicle going on and off the strip. 95

In Fig. XI, I have shown a pair of strips 100 formed on their under sides with depending tapered spikes *p*. The spikes *p* when properly embedded within a road-bed prevent any lateral displacement or circumferential movement of the strips. The strips are 105 connected by means of metal rods *s*, the opposite ends of such rods being bent at an angle and embedded within the strips, as shown. By means of the rod *s*, relative movement of the strips is prevented so that they 110 are maintained in proper spaced relation at all times. It will be noted that by virtue

of the fact that the ends of the rod are embedded within the strips, the rod is utilized as a reinforcement for the strips.

I claim:—

5. 1. A roadway consisting of parallel continuous strips of material which are capable of being molded *in situ* in trenches formed in said roadway, the upper surfaces of said strips being level with the surface of the 10 roadway and of a width sufficient to accommodate vehicles of varying wheel gage using the strips; and metal reinforcement embedded in and entirely inclosed by the material of said strips, so that neither air nor 15 moisture can have access to said reinforcement.
2. A roadway consisting of parallel continuous strips of material which are capable

of being molded *in situ* in trenches formed in said roadway, the upper surfaces of said strips being level with the surface of the roadway and approximately rectangular in cross-section and of a width sufficient to accommodate vehicles of varying wheel gage using said strips, and metal reinforcement, 25 embedded in and entirely inclosed by the material of said strips, so that neither air nor moisture can have access to said reinforcement.

Signed at Dundee, in the county of For- 30 far, Scotland.

JAMES CHAPMAN.
